LOOPER OPERATING MECHANISM FOR
SEWING MACHINESOscar Quist, Chicago, Ill., assignor to Union
Special Machine Company, Chicago, Ill., a cor-
poration of Illinois

Application February 17, 1951, Serial No. 211,457

16 Claims. (Cl. 112—200)

1

This invention relates to sewing machines and more particularly to the looper operating mechanisms of machines of the type adapted to form a two-thread chain stitch. It is especially applicable to machines of the flat-bed type having a drive shaft which extends longitudinally of the base of the machine frame and particularly those adapted for the production of bags or the closing of filled bags.

A primary object of the invention has been to provide connections from the drive shaft to the looper of a machine of the foregoing character, for imparting loop seizing and shedding movements thereto, which are of simple construction, durable and reliable in their operation and which may be readily disconnected or modified manually at will to enable the movement of the looper into a more accessible position for threading.

Another object has been to provide connections of the above indicated character which have readily accessible, and easily manipulable means for disconnecting and reconnecting, or otherwise modifying, the connections for the purposes stated.

A further object has been to provide connections of the foregoing character in a machine in which the looper is of the four-motion type, i. e., is given both loop seizing and shedding movements and needle avoid movements.

Still another object has been to so construct and arrange the means for imparting the four motions of the looper of a machine of the character indicated that the main wear receiving parts may be fully enclosed in a lubricant retaining chamber. This feature is particularly applicable to machines intended for the production of bags or the seaming of similar flat articles.

Other objects, features, and advantages of the invention will appear from the detailed description of an illustrative embodiment of the same which will now be given in conjunction with the accompanying drawings, in which:

Fig. 1 is a view, largely in front elevation, of a machine embodying the invention, portions of the frame being broken away and other portions being shown in vertical section;

Fig. 2 is a horizontal sectional view through the machine taken just below the work supporting surface, certain parts of the frame below said plane being broken away for clearer illustration of other parts;

Fig. 3 is a detail view, in vertical section along the line 3—3 of Fig. 2, showing the connections from the drive shaft for imparting needle avoid movements to the looper;

Fig. 4 is an enlarged detail view, largely in elevation but partly in section, showing the connections for imparting loop seizing and shedding movements to the looper;

Fig. 5 is an enlarged detail view of connections from the drive shaft to the needle lever;

Fig. 6 is an elevational view of the looper and its supporting means, as viewed from the left in Fig. 1;

Fig. 7 is a detail view of a pin forming part of the looper operating connections;

Fig. 8 is a face view of a washer element that is mounted on the pin; and

Fig. 9 is a horizontal sectional view, similar to Fig. 2, but illustrating a modified frame construction and modified means for imparting needle avoid movements to the looper.

In the drawings the machine has been illustrated in the conventional position assumed for the seaming of flat work, as in the production of bags. It will be understood that when the machine is used for the closing of filled bags, its position will be such that the work supporting surface will be disposed in a vertical plane, i. e., the base and the overhanging arm will have their longitudinal axes disposed vertically, rather than horizontally, and the driving pulley will be at the top. The machine will be supported by a pedestal or the like in substantially the same position as that shown in the patent to Kucera et al. No. 1,577,472, granted March 23, 1926.

The frame of the machine comprises a base 10 having a work supporting surface 11 from one end of which rises a standard 12. An overhanging arm 13 projects laterally from the upper end of the standard and terminates in a needle head 14. A main drive shaft extends longitudinally of the base and is journaled in suitable bearings therein. To facilitate assembly the shaft is formed in two sections 15 and 15a (Fig. 2) which are joined by a coupling 15b to provide in effect a single continuous shaft. At its right end the shaft projects from the frame and carries a combined handwheel and pulley 16 through which power may be supplied by a belt, from any suitable source, for operating the machine. A crank portion 17 of the drive shaft, in the region of the standard 12, carries a strap member 18. Needle bearings 18a (Fig. 5) are preferably provided between the crank 17 and the strap 18 to reduce friction. A pin 19 extending laterally at the lower end of a pitman 20, and suitably secured thereto, serves to connect the pitman pivotally with upstanding ears 18b integral with the strap member 18. At its upper end the pitman 20 carries a strap 21 which cooperates with a ball pin

22 (Figs. 1 and 5) projecting from the end of a needle lever 23 pivotally mounted within the overhanging arm for rocking movement about an axis 24. The opposite end of the needle lever is connected by a link 25 with a block 26 secured to a needle bar 27 which is mounted for vertical reciprocation in bearing sleeves 28 and 29 carried by the needle head. As will be apparent, the needle lever will be oscillated on each revolution of the drive shaft 15 through the connections described from the crank 17. These connections are such that friction is held to a minimum. Binding of the parts is eliminated by the pivotal connection at 19 and the spherical surfaces of the strap 21 and the ball pin 22. It will be understood that the needle bar 27 carries a needle at its lower end which is reciprocated through the work between successive feeding movements of the latter along the work supporting surface 11.

Cooperating with the needle in the formation of stitches is a looper 30 (Figs. 1, 4 and 6) which is mounted on the upper end of a looper carrier 31 pivotally supported by a bolt 32, mounted in a manner to be hereinafter described. The shank of the looper 30 is retained in the upper end of the arm 31 by a set screw 33. Intermediate its ends, the looper carrying arm 31 is provided with a laterally extending ball pin 34 which receives a strap portion 35 of an extensible link 36. At its opposite end the link 36 carries a strap 37 cooperating with a ball pin 38 extending laterally from an arm 39. This arm forms part of a rock member 40 which is mounted for free rocking movement about a shaft 41 that is suitably journaled in the base of the frame and extends laterally thereof. Rock member 40 has also integrally formed therewith two spaced parallel arms 42 and 42a which project radially from the axis of the member at an angle of about 90° in relation to the arm 39. A pin 43 (Fig. 7), having an enlarged head which is accessible at the front of the base, is slidably mounted in aligned openings in the arms 42 and 42a. A spring 44, compressed between the inner face of the arm 42a and a cupped, U-shaped washer 45 (Fig. 8) mounted on the pin, serves to urge the latter inwardly to a position in which its end 43a is seated in an opening in an arm 46 that extends radially from a sleeve 47. Washer 45 is slipped over a reduced portion 43b of the pin and is urged by the spring against a shoulder 43c on the pin. Sleeve 47 is secured by one or more screws 48 to the shaft 41. Means to be presently described are provided for rocking the sleeve 47 and shaft 41. A collar 50 secured to the outer end of the shaft 41 prevents axial movement of the latter in one direction, while the sleeve 47 and rock member 40 prevent axial movement in the opposite direction.

For rocking the sleeve 47 the latter has an integral, downwardly and laterally extending socket portion 51 (Figs. 2 and 4) arranged to receive the shank of a ball pin 52. The latter cooperates with a strap 53 at the lower end of a pitman having a strap 54 surrounding a spherical eccentric 55 on the drive shaft 15a. It will be seen that through the connections described, the sleeve 47 and shaft 41 will be oscillated upon each revolution of the main drive shaft. The oscillatory movements of the sleeve will, in turn, be imparted to the rock member 40 whenever the inner end of the pin 43 is engaged with the opening in the arm 46. However, this connection may be broken by a simple outward pull upon the head of the pin 43. A slight downward movement of the pin after it is disengaged from the

arm 46 will rock the member 40 about the shaft 41. Such rocking movement may be effected manually or by gravity or may be facilitated by a spring, if desired. The extent of the movement, however, is limited by the cooperation of the inner end of a screw 56, carried by the arm 42, with the wall of an enlarged opening 57 (Fig. 4) in the arm 46. The arrangement is such that the relative movement between the arms 42 and 46, permitted by the screw 56, is sufficient to carry the looper into an accessible position for threading. For greatest accessibility of the looper the handwheel 16 should be turned until the looper is in its most retracted position. After threading of the needle the parts may be readily restored to their normal operating condition by slight upward movement of the pin 43 to realign its inner end with the opening in the arm 46, at which time the spring 44 will urge the pin into its coupling position.

For the purpose of imparting needle avoid movements to the looper the bolt 32 upon which it is pivotally mounted is carried by an axial extension 58a of a collar 58b integral with or otherwise secured to a rock shaft 58 (Fig. 2). This rock shaft is journaled in bearings 59 and 60 carried by the frame of the machine. Axial movement of the shaft is prevented by the collar 58b and a collar 58c secured to the opposite end of the shaft. Rocking movements are imparted to the shaft by the connections best shown in Fig. 3. These include an arm 61 clamped to the shaft by means of a screw 62. A pin 63 carried by the arm 61 adjacent its free end serves to connect the arm pivotally with a pitman 64 which cooperates with an eccentric 65 on the shaft 15a. It will be understood that the needle avoid movements are imparted to the looper by the connections described in properly timed relation to the loop seizing and shedding movements imparted by the eccentric 55 and to the reciprocations of the needle.

It will be understood that the machine is provided with suitable work feeding mechanism, preferably of the four motion feed dog type, spring urged presser means for holding the work against the throat plate and the feed dog, thread controlling and guiding means, and the like. When used as a filled bag closing machine it is preferably equipped with an automatic thread chain cutter, such as that disclosed in the patent to Sauer No. 2,360,284, granted October 10, 1944, for severing the chain between bags. Other accessory devices may also be included, but since these form no part of the present invention no description thereof need be given.

As best shown in Fig. 2 the base portion of the frame is reduced in width at its left end to facilitate the movement through the machine of the necks of filled bags. The cutting away of the frame, as indicated in the upper left hand corner of Fig. 2, has necessitated certain changes in the form and arrangement of various parts of the work feeding mechanism from those employed in an ordinary flat bed machine. These changes are not required for machines intended for the production of bags.

In Fig. 9 there is illustrated a modified construction in which the base portion of the frame is provided with an enclosed lubricant retaining housing. This serves to enclose the operating means for imparting the loop seizing and shedding movements and the needle avoid movements to the looper and portions of the feed operating mechanism. The principal differences between this construction and that shown in Fig. 2 are in

to said looper carrier for rocking the latter about its pivot to impart loop seizing and shedding movements to said looper, and connections from said shaft for rocking said looper support to impart needle avoid movements to said looper.

6. In a machine of the class described having a frame and a drive shaft carried thereby, a looper support rockably mounted in said frame, a looper carrier pivotally mounted on said support, a looper carried by said carrier, means for shifting said carrier about its pivot to impart loop seizing and shedding movements to said looper comprising a plurality of rock members mounted for rocking movement about a common axis, connections from said shaft for rocking one of said members, readily disconnectible connections for causing rocking of said members in unison, connections from the other of said members to said carrier for shifting the same about its pivot upon rocking movement of said other of said members, and connections from said shaft for rocking said support to impart needle avoid movements to said looper.

7. In a machine of the class described having a frame and a drive shaft carried thereby, a looper support rockably mounted in said frame, a looper carrier pivotally mounted on said support, a looper carried by said carrier, means for shifting said carrier about its pivot to impart loop seizing and shedding movements to said looper comprising a plurality of rock members mounted for rocking movement about a common axis, connections from said shaft for rocking one of said members, readily disconnectible connections for causing rocking of said members in unison, connections from the other of said members to said carrier for shifting the same about its pivot upon rocking movement of said other of said members, interengaging means on said members for limiting relative movement therebetween upon disconnection of said readily disconnectible connections, and connections from said shaft for rocking said support to impart needle avoid movements to said looper.

8. In a machine of the class described having a frame and a drive shaft carried thereby, a looper support rockably mounted in said frame, a looper carrier pivotally mounted on said support, a looper carried by said carrier, means for shifting said carrier about its pivot to impart loop seizing and shedding movements to said looper comprising a plurality of rock members mounted for rocking movement about a common axis, connections from said shaft for rocking one of said members, readily disconnectible connections for causing rocking of said members in unison, connections from the other of said members to said carrier for shifting the same about its pivot upon rocking movement of said other of said members, said last mentioned connections including a link pivotally connected at one end to said carrier and pivotally connected at its other end to said other of said members, and connections from said shaft for rocking said support to impart needle avoid movements to said looper.

9. In a machine of the class described having a frame and a drive shaft carried thereby, a looper support rockably mounted in said frame, a looper carrier pivotally mounted on said support, a looper carried by said carrier, means for shifting said carrier about its pivot to impart loop seizing and shedding movements to said looper comprising a plurality of rock members mounted for rocking movement about a common axis, connections from said shaft for rocking one of said

members, readily disconnectible connections for causing rocking of said members in unison, connections from the other of said members to said carrier for shifting the same about its pivot upon rocking movement of said other of said members, said last mentioned connections including a link pivotally connected at one end to said carrier and pivotally connected at its other end to said other of said members, interengaging means on said members for limiting relative movement therebetween upon disconnection of said readily disconnectible connections, and connections from said shaft for rocking said support to impart needle avoid movements to said looper.

10. In a machine of the class described having a frame and a drive shaft carried thereby, a pivotally mounted looper carrier, a looper carried by said carrier, means for shifting said carrier about its pivot to impart loop seizing and shedding movements to said looper comprising a plurality of rock members mounted for rocking movement about a common axis, connections from said shaft for rocking one of said members, readily disconnectible connections for causing rocking of said members in unison, connections from the other of said members to said carrier for shifting the same about its pivot upon rocking movement of said other of said members, said last mentioned connections including a link pivotally connected at one end to said carrier and at the other end to said other of said members, and means carried by one of said members cooperating with the other of said members for limiting relative movement thereof.

11. In a machine of the class described having a frame and a drive shaft carried thereby, a looper support rockably mounted in said frame, a looper carrier pivotally mounted on said support, a looper carried by said carrier, means for shifting said carrier about its pivot to impart loop seizing and shedding movements to said looper comprising a plurality of rock members mounted for rocking movement about a common axis, connections from said shaft for rocking one of said members, a spring urged plunger arranged for manual manipulation exterior of said frame for disconnectibly connecting said members for rocking movement in unison, connections from the other of said members to said carrier for shifting the same about its pivot upon rocking movement of said other of said members, and connections from said shaft for rocking said support to impart needle avoid movements to said looper.

12. In a machine of the class described having a frame and a drive shaft carried thereby, a looper support rockably mounted in said frame, a looper carrier pivotally mounted on said support, a looper carried by said carrier, means for shifting said carrier about its pivot to impart loop seizing and shedding movements to said looper comprising a plurality of rock members mounted for rocking movement about a common axis, connections from said shaft for rocking one of said members, readily disconnectible connections for causing rocking of said members in unison, connections from the other of said members to said carrier for shifting the same about its pivot upon rocking movement of said other of said members, said last mentioned connections including a link having ball-joint pivotal connections at its two ends with said carrier and said other of said members, respectively, and connections from said shaft for rocking said support to impart needle avoid movements to said looper.

13. In a sewing machine having a frame with

the form and arrangement of certain parts of the looper operating mechanism. The bolt 32, upon which the looper carrier 31 is pivotally mounted, is carried by an extension 66 of a collar 67 integral with or otherwise secured to a rock shaft 68. The latter is longer than the rock shaft 58 of Fig. 2 and is journaled in bearings 69, 70, and 71 provided in suitable walls or partitions in the base of the frame. A collar 72 secured to the shaft 68 at the opposite end of the bearing 69 from the collar 67 cooperates with the latter to retain the shaft against axial movement. As will be seen, the shaft 68 extends completely through an enclosed chamber formed between walls 73, 74, 75 and 76 of the frame. This chamber may be supplied with lubricant to a suitable level for the lubrication of the relatively sliding surfaces within it. The only openings through the walls of the chamber are those which carry the bearings for the various shafts. Little or no lubricant can escape, particularly when the machine is used as a conventional flat-bed machine for the production of bags and the like.

Rocking of the shaft 68 to impart needle avoid movements to the looper is effected by an eccentric on the drive shaft 15 which cooperates with a strap portion 77 of a pitman which, at its lower end, is pivotally connected with an arm 78 secured to the shaft 68. These connections may be substantially the same as the corresponding parts shown in Fig. 3. The means for imparting loop seizing and shedding movements to the looper also differ somewhat from the form shown in Fig. 2. Thus the shaft 49 is journaled in three bearings 79, 80 and 81, bearing 80 extending through the wall 76 of the enclosed chamber. For rocking the shaft there is secured thereto, within the chamber, a sleeve 82 having a socket portion 83, similar to part 51 of Fig. 4, which carries the ball pin 52 through which the sleeve and shaft are rocked by the eccentric 55. An arm 84, corresponding with arm 46 of Figs. 2 and 4, is formed as a separate member and is secured to the shaft 49 outside of the chamber adjacent the arm 42 of rock member 40. In other respects this mechanism is the same as described in connection with Figs. 2 and 4 and operates in the same manner.

It will be noted that the arrangement of Fig. 9 provides for the complete enclosure of the eccentrics and connections therefrom to the shafts which impart both the loop seizing and shedding movements and the needle avoid movements to the looper. Any suitable means may be employed for dispersing the lubricant within the enclosed chamber to insure adequate and continuous lubrication of the enclosed parts.

While a preferred embodiment of the invention has been described in considerable detail and certain modifications have been suggested, it will be understood that various other changes may be made in the construction and arrangement of the several parts without departing from the general principles and scope of the invention as defined by the appended claims.

What I claim is:

1. In a sewing machine having a main drive shaft and stitch forming devices including a pivotally mounted looper carrier carrying a looper, the combination of connections from said shaft to said looper carrier for imparting loop seizing and shedding movements to said looper, which comprise a rock member, connections from said shaft to said rock member for oscillating the latter, a member oscillatable about the axis of said rock member, readily disconnectible means

for connecting said oscillatable member with said rock member for oscillation in unison, and connections from said oscillatable member to said looper carrier for rocking the latter about its pivot to impart loop seizing and shedding movements to the looper.

2. In a sewing machine having a main drive shaft and stitch forming devices including a pivotally mounted looper carrier carrying a looper, the combination of connections from said shaft to said looper carrier for imparting loop seizing and shedding movements to said looper, which comprise a rock member, connections from said shaft to said rock member for oscillating the latter, a member oscillatable about the axis of said rock member, readily disconnectible means for connecting said oscillatable member with said rock member for oscillation in unison, and connections from said oscillatable member to said looper carrier for rocking the latter about its pivot to impart loop seizing and shedding movements to the looper, said looper being shiftable to a threading position upon disconnection of said readily disconnectible means, and interengaging means carried by said members for limiting relative movement therebetween upon disconnection of said disconnectible means.

3. In a sewing machine having a main drive shaft and stitch forming devices including a pivotally mounted looper carrier carrying a looper, the combination of connections from said shaft to said looper carrier for imparting loop seizing and shedding movements to said looper, which comprise a rock member mounted for oscillation about an axis transverse to the axis of said shaft, connections from said shaft to said rock member for oscillating the latter, a member oscillatable about the axis of said rock member, readily disconnectible means for connecting said oscillatable member with said rock member for oscillation in unison, and connections from said oscillatable member to said looper carrier for rocking the latter about its pivot to impart loop seizing and shedding movements to the looper.

4. In a sewing machine having a main drive shaft and stitch forming devices including a rockably mounted looper support and a looper carrier pivotally mounted on said support and carrying a looper, the combination of connections from said shaft to said looper carrier for imparting loop seizing and shedding movements to said looper, which comprise a rock member, connections from said shaft to said rock member for oscillating the latter, a member oscillatable about the axis of said rock member, readily disconnectible means for connecting said oscillatable member with said rock member for oscillation in unison, and connections from said oscillatable member to said looper carrier for rocking the latter about its pivot to impart loop seizing and shedding movements to the looper.

5. In a sewing machine having a main drive shaft and stitch forming devices including a rockably mounted looper support and a looper carrier pivotally mounted on said support and carrying a looper, the combination of connections from said shaft to said looper carrier for imparting loop seizing and shedding movements to said looper, which comprise a rock member, connections from said shaft to said rock member for oscillating the latter, a member oscillatable about the axis of said rock member, readily disconnectible means for connecting said oscillatable member with said rock member for oscillation in unison, connections from said oscillatable member

a work supporting base, a shaft extending longitudinally of said base, means for advancing work transversely across the base and stitch forming devices including a looper having loop seizing and shedding movements across the line of feed, the combination which comprises a pivotally mounted looper carrier, a pair of rock members mounted on an axis transverse to the axis of said shaft, connections from said shaft to one of said members for rocking the same, manually disconnectible means for connecting said members for rocking in unison, and a link pivotally connected at its two ends with said carrier and the other of said members, respectively.

14. In a sewing machine having a frame with a work supporting base, a shaft extending longitudinally of said base, means for advancing work transversely across the base and stitch forming devices including a looper having loop seizing and shedding movements across the line of feed, the combination which comprises a pivotally mounted looper carrier, a pair of rock members mounted on an axis transverse to the axis of said shaft, connections from said shaft to one of said members for rocking the same, a spring urged plunger serving to connect said members for rocking movement in unison, said plunger having a manually engageable portion accessible at the front of said frame for shifting said plunger into an inactive position, and a link pivotally connected at its two ends with said carrier and the other of said members, respectively.

15. In a sewing machine having a frame with a work supporting base, a shaft extending longitudinally of said base, means for advancing work transversely across the base and stitch forming devices including a looper having loop seizing and shedding movements across the line of feed, the combination which comprises a pivotally mounted looper carrier, a pair of rock members mounted on an axis transverse to the axis of said shaft, connections from said shaft to one of said members for rocking the same, manually disconnectible means for connecting said members for rocking in unison, and a link pivotally connected at its two ends with said carrier and the other of said members, respectively.

10 to one of said members for rocking the same, a spring urged plunger serving to connect said members for rocking movement in unison, said plunger having a manually engageable portion accessible at the front of said frame for shifting said plunger into an inactive position, interengaging means carried by said members for limiting relative movement therebetween when said plunger is in its inactive position, and a link pivotally connected at its two ends with said carrier and the other of said members, respectively.

16. In a sewing machine having a frame with a work supporting base having an enclosed lubricant retaining chamber, a shaft extending longitudinally of said base, means for advancing work transversely across the base and stitch forming devices including a looper having loop seizing and shedding movements across the line of feed, the combination which comprises a looper support rockable about an axis parallel with said shaft, a looper carrier pivotally mounted on said support for pivotal movement about an axis transverse to that of said support, a pair of rock members mounted on an axis transverse to the axis of said shaft, connections from said shaft to one of said members for rocking the same, connections from said shaft for rocking said support, both of said connections being at least partly disposed within said enclosed chamber, manually disconnectible means for connecting said members for rocking in unison, and a link pivotally connected at its two ends with said carrier and the other of said members, respectively.

OSCAR QUIST.
